UNITED STATES PATENT OFFICE

2,439,904

FILAMENT COILING APPARATUS

Julius Petersen, Cleveland Heights, Ohio, assignor
to General Electric Company, a corporation of
New York

Application August 1, 1945, Serial No. 608,257

11 Claims. (Cl. 153—67)

1

My invention relates, in general, to apparatus for coiling fine wire into filaments for electric incandescent lamps and other similar electrical devices, and more particularly to a gripper device for holding an end of the filament wire to be coiled.

In certain types of filament forming machines for the production of coiled lamp filaments having straight end legs extending laterally from the coil axis, the filament wire is fed transversely to and coiled on a forming mandrel. The free end of the filament wire is first positioned and held across the mandrel by a gripper device carried by the coiling spindle of the machine, and the mandrel and gripper are then rotated in unison to coil the filament wire around the mandrel.

The filament wire gripper heretofore in use on such type of filament forming machines has comprised a slide member which is slidable longitudinally of the mandrel and is provided with a thin lip or plate-like jaw portion which extends laterally of the mandrel and which clamps the filament wire end or leg portion against a flat surface on the end of the coiling spindle. With such type grippers, the coiling spindle which carries the gripper can be rotated only through a number of complete revolutions (i. e., no additional fraction of a revolution is possible) since the gripper, in order to properly clamp the filament wire at the start of each coiling cycle, must always be positioned in the same rotative starting position. This requirement therefore limits the use of the machine insofar as concerns the production of different types of filaments having different positioning of the filament legs angularly about the coil axis. Moreover, to permit the jaw of such type grippers to be set as close as possible to the mandrel without interfering with the first turn of the filament coil on the mandrel, the jaw was formed thin enough to enter the space between the leg portion and the first turn of the filament, which space is very small in the case of filaments of incandescent lamps and similar devices. Since the gripper always had to be positioned in the same rotative starting position, the filament wire was therefore engaged and clamped by the same portion of the jaw gripping face during each filament coiling cycle, thus concentrating the wear on the jaw at one point. Because of the resulting excessive wear on the jaw and their relatively thin section, such a jaw would either break or wear out in a relatively short period of time thus necessitating its replacement from time to time.

One object of my invention is to provide an improved filament wire gripping device for filament

2

coiling machines which will effectively grip the filament wire in any rotative position of the coiling spindle on which the gripper is mounted.

Another object of my invention is to provide a filament wire gripping device the wear-undergoing parts of which are of sturdier construction and much longer life than the corresponding parts of the gripping devices heretofore in use.

Further objects and advantages of my invention will appear from the following detailed description of a species thereof and from the accompanying drawing, in which:

Fig. 1 is a fragmentary elevation of the coiling head of a filament forming machine provided with a filament wire gripping device according to the invention; Fig. 2 is an enlarged plan view, partly in section, of the gripping device; and Fig. 3 is a section on the line 3—3 of Fig. 2.

Referring to the drawings, the filament wire gripper or chuck 1 comprising my invention is there shown as applied to the coiling head A of a filament forming machine of the type wherein the filament wire is fed transversely to and coiled on a forming mandrel. Such a machine is described and claimed in co-pending application Serial No. 608,115, Fred B. Iden, filed of even date herewith. The coiling head A comprises a hollow spindle 2 extending through and journaled in a bearing 3 mounted on the table 4 of the machine. At its inner end, the coiling spindle 2 carries the filament wire gripper 1 and an axially extending mandrel 5 on which the filament wire 6 is coiled. The mandrel 5, which normally projects outwardly beyond the nose of the gripper 1, extends through the gripper and is held at its inner end in a mandrel chuck 7 carried by a mandrel rod 8 reciprocable within the coiling spindle 2. During the operation of the machine, the gripper 1 and mandrel 5 are intermittently rotated in unison about the mandrel axis to thereby draw and wind the filament wire 6 around the mandrel.

The gripper 1 according to the invention comprises inner and outer sleeve members 9 and 10, respectively, which are longitudinally slidable relative to one another. The inner end of the inner sleeve 9 projects outwardly beyond the corresponding end of the outer sleeve 10 and is provided with a screw thread 11 which is screwed into a threaded socket 12 in the inner end of the coiling spindle 2 to thereby secure the inner sleeve to the coiling spindle in coaxial alignment with one another. At its outer end, the inner sleeve 9 carries a combination mandrel guide die and inner jaw member 13 in the form of a headed pin the stem portion 14 of which extends into

and fits snugly within the bore 15 of the inner sleeve while the head portion 16 of which overlies and abuts against the outer end of the inner sleeve. The mandrel guide pin 13 is provided with an axially extending guide opening 17 for receiving and guiding the mandrel 5. The outer face 18 of the head portion 16 of the pin is either in the form of a flat surface extending transversely of the mandrel 5, or a cone-shaped surface as shown, depending upon whether the filament legs are to extend from the filament coil in a direction at right angles, or other than at right angles to the axis of the filament coil. The pin 13 and the inner sleeve 9 are rotatively locked together, as by a set screw 19 threaded into the inner sleeve and extending into a keyway 20 in the stem portion 14 of the pin.

At its outer end, the outer sleeve 10 is provided with a radially inturned annular flange or ring 21 which overlies the face 18 of the pin head 16. The inner face 22 of the flange 21 is shaped to conform to the face 18 of the pin head 16 so as to form, together with the said face 18, opposed annular jaw faces for gripping an end of the filament wire therebetween. In the particular case illustrated, the gripping faces 18, 22 are shown tapered at an angle of approximately 8° to conform to the approximately 8° pitch angle of the particular filament coil which the machine, as shown in the drawings, is set up to form. The flange 21 is continuously urged towards the head 16 of pin 13, to thereby clamp the free end portion of the filament wire 6 therebetween, by the force of a compression coil spring 23 fitting over the inner sleeve 9 and compressed between an annular flange 24 extending radially outward from the outer end of the inner sleeve 9 and a retainer ring 25 disposed within and secured to the outer sleeve 10. The flange 21 and the head 16 of the mandrel guide pin 13 thus constitute outer and inner annular jaw members, respectively, which are spring-pressed together to grip and hold the filament wire tightly therebetween. The inner and outer sleeves 9 and 10 are rotatively interlocked, so as to rotate in unison, by a pin 26 fitting into aligned openings 27 and 28 located, respectively, in the inner end of the outer sleeve and in an annular flange 29 which extends radially outward from the inner sleeve and overlies the inner end of the outer sleeve. To permit assembly of the ring 25 and spring 23 on the inner sleeve 9 between the flanges 24 and 29 thereon, the retainer ring is formed in two half-sections each one of which is secured to the outer sleeve 10 by a fastening screw 30 while the flange 24 is provided with a diagonal slot 31 in its periphery through which the spring 23 is threaded.

During operation of the filament forming machine, the jaw portions 16 and 21 of the chuck 1 are intermittently separated to allow insertion of the free end portion of the filament wire 6 through the central opening 32 of flange 21 and into the space between the annular jaw faces 18, 22, and to subsequently release the said wire portion following the coiling operation. The separation of the annular jaws 16, 21 is effected by a cam-operated lever 33 pivotally mounted on the coiling spindle bearing 3, and the insertion of the filament wire end into the separated jaws is effected by the movement towards the mandrel of filament wire feed means 38 operating in timed relation with the lever 33, as described in the above mentioned co-pending application. The lever 33 is provided at one end with spaced arms 34 which span the inner end of the coiling spindle

2 and are provided with pins 35 for engagement with a radially outward extending flange 36 on the outer sleeve 10. When the lever 33 is pivoted in its chuck-opening direction, the pins 35 engage the flange 36 and move the outer sleeve 10 forwardly relative to the inner sleeve 9, against the resistance of the spring 23, to thereby separate the jaw faces 18 and 22 of the chuck. When the lever 33 is pivoted in the opposite direction so as to disengage the pins 35 from the flange 36, the chuck spring 23 forces the outer sleeve 10 backwardly, thus closing the chuck jaws 16 and 21 and clamping the end of the filament wire tightly between the jaw faces 18, 22. The lever 33 is normally held in its inoperative position out of engagement with the flange 36 of sleeve 10 by a cam (not shown) mounted on the cam shaft of the machine, while it is pivoted to its chuck-opening position by the expansive force of a compression coil spring 37 compressed between the lever and the spindle bearing 3. Obviously, to effect the opening of the chuck 1, it is necessary that the opening force applied to the outer sleeve 10 by the lever 33 and spring 37 be greater than the closing force exerted on the said sleeve 10 by the coil spring 23 within the chuck.

The provision of ring-shaped jaw surfaces 18, 22 surrounding the mandrel 5 permits the filament leg to be gripped to start coiling at any point on the complete 360° circle around the mandrel. Such feature permits a definite improvement in coil quality and uniformity. By being able to grip the filament leg at any point around the circular extent of the chuck jaws 16 and 21, it is possible to wind the required number of coil turns on the mandrel plus any fraction of a turn necessary to bring the legs of the filament coil in proper relation to each other. Such feature also permits the wear on the jaw faces 18, 22, incident to operation of the machine, to be more or less uniformly distributed over the circular extent of the jaw faces by merely changing the rotative starting position of the coiling spindle 2 at periodic intervals. Furthermore, the sturdier construction and longer life of the chuck jaw members 16 and 21, as compared to those heretofore in use, provides a considerable saving in maintenance and parts replacement cost.

If desired, the combination mandrel guide die and jaw member 13 may be formed integral with the inner sleeve member 9. However, I prefer to make it as a separate element in order to permit interchange thereof with other die members having different sized mandrel guide openings 17 and/or differently tapered wire gripping surfaces 18. Where the die member 13 is replaced by one having a differently tapered gripping surface 18, the outer sleeve 10 is also replaced by one having a correspondingly tapered gripping surface 22. By selecting the proper angle of taper of the gripping surfaces 18, 22, it is possible to produce filaments having legs extending from the coil at an angle corresponding to the pitch angle of the coil, which filament construction is usually desirable.

What I claim as new and desire to secure by Letters Patent of the United States is:

1. A filament wire gripper for filament coiling apparatus comprising inner and outer sleeve members slidably relative to one another, a mandrel guide pin fitting within the hollow interior of and rotatively interlocked with the inner sleeve member, said pin having an axially extending mandrel guide opening and having its outer end located outwardly beyond the outer end of the

inner sleeve member and formed as an annular jaw face surrounding said opening, said outer sleeve member being provided at its outer end with an inturned annular flange having an annular jaw face overlying and opposed to the jaw face of said pin, and resilient means acting on one of said sleeve members to resiliently urge the opposed jaw faces together.

2. A filament wire gripper for filament coiling apparatus comprising inner and outer sleeve members slidable relative to one another, a headed pin rotatively interlocked with said inner sleeve member and having its stem portion extending into and fitting within the hollow interior of the inner sleeve member and its head portion overlying and abutting against the outer end of the said inner sleeve member, said pin having an axially extending mandrel guide opening and having the outward side of its head portion formed as an annular jaw face surrounding said opening, said outer sleeve member being provided at its outer end with an inturned annular flange having an annular jaw face overlying and opposed to the jaw face of said pin, and resilient means acting on one of said sleeve members to resiliently urge the opposed jaw faces together.

3. A head for filament coiling apparatus comprising a coiling spindle having an axially extending mandrel guide opening at one end thereof, and a coiling mandrel extending axially of said spindle through said guide opening and slidably therein to project outwardly beyond the said spindle end, said spindle being provided at said end with a pair of opposed annular jaw members surrounding said mandrel, said jaw members being relatively movable axially of the spindle and resiliently urged towards one another to clamp an end of the filament wire therebetween and hold it across the portion of the mandrel projecting outwardly beyond the said spindle end.

4. A head for filament coiling apparatus comprising a coiling spindle having an axially extending mandrel guide opening at one end thereof, a coiling mandrel extending axially of said spindle through said guide opening and slidably therein to project outwardly beyond the said spindle end, a sleeve member surrounding the said end of the coiling spindle and provided with an inturned annular flange surrounding said mandrel and overlying the said spindle end, said spindle being provided at said end with an annular jaw surface surrounding said mandrel and opposed to the said annular flange, and resilient means acting on said sleeve member to resiliently urge the said flange thereof towards the said annular jaw surface to clamp an end of the filament wire therebetween.

5. A filament wire gripper for filament coiling apparatus comprising a sleeve member having an axially extending mandrel guide opening, a coiling mandrel extending axially of said sleeve through said guide opening and slidably therein to project outwardly beyond one end of said sleeve, an annular jaw member surrounding said mandrel and opposed to the said end of the sleeve, said sleeve being rotatively interlocked with said jaw member and being provided at said end with an annular jaw surface surrounding said mandrel and facing said annular jaw member, and resilient means acting on said jaw member to resiliently urge it towards the said jaw surface to clamp an end of the filament wire therebetween.

6. A filament wire gripper for filament coiling apparatus comprising inner and outer rotatively

interlocked sleeve members slidable relative to one another, said inner sleeve member having an axially extending mandrel guide opening, a coiling mandrel extending axially of said inner sleeve member through said guide opening and slidably therein to project outwardly beyond one end of said inner sleeve, said outer sleeve member being provided at one end with an inturned annular flange surrounding said mandrel and having an annular jaw face opposed to the said end of the inner sleeve member, said inner sleeve member being provided at said end with an annular jaw face surrounding said mandrel and facing the jaw face of said outer sleeve member, and resilient means acting on one of said sleeve members to resiliently urge the opposed jaw faces together.

7. A filament wire gripper for filament coiling apparatus comprising inner and outer sleeve members slidable relative to one another, said inner sleeve member having an axially extending mandrel guide opening, a coiling mandrel extending axially of said inner sleeve member through said guide opening and slidably therein to project outwardly beyond one end of said inner sleeve, said outer sleeve member being provided at one end with an inturned annular flange surrounding said mandrel and having an annular jaw face opposed to the said end of the inner sleeve member, said inner sleeve member being provided at said end with an annular jaw face surrounding said mandrel and facing the jaw face of said outer sleeve member, resilient means acting on one of said sleeve members to resiliently urge the opposed jaw faces together, and interengaging means on said inner and outer sleeve members rotatively locking said members together.

8. A filament wire gripper for filament coiling apparatus comprising inner and outer rotatively interlocked sleeve members slidable relative to one another, said inner sleeve member having an axially extending mandrel guide opening, a coiling mandrel extending axially of said inner sleeve member through said guide opening and slidably therein to project outwardly beyond one end of said inner sleeve, said outer sleeve member being provided at one end with an inturned annular flange surrounding said mandrel and having an annular jaw face opposed to the said end of the inner sleeve member, said inner sleeve member being provided at said end with an annular jaw face surrounding said mandrel and facing the jaw face of said outer sleeve member, and a compression coil spring compressed between and acting on said sleeve members to resiliently urge the opposed jaw faces together.

9. A filament wire gripper for filament coiling apparatus comprising inner and outer rotatively interlocked sleeve members slidable relative to one another, said inner sleeve member having an axially extending mandrel guide opening, a coiling mandrel extending axially of said inner sleeve member through said guide opening and slidably therein to project outwardly beyond one end of said inner sleeve, said outer sleeve member being provided at one end with an inturned annular flange surrounding said mandrel and having an annular jaw face opposed to the said end of the inner sleeve member, said inner sleeve member being provided at said end with an annular jaw face surrounding said mandrel and facing the jaw face of said outer sleeve member, and a compression coil spring disposed within the outer sleeve member and fitting over the inner sleeve member, said coil spring being compressed between shoulders on said sleeve members to resiliently urge the opposed jaw faces together.

iently urge the opposed jaw faces thereof together.

10. A filament wire gripper for filament coiling apparatus comprising rotatively interlocked inner and outer sleeve members slidable relative to one another and mounted on one end of a coiling spindle, said inner sleeve member having an axially extending mandrel guide opening and being provided with an external collar adjacent its outer end, a coiling mandrel extending axially of said spindle through said guide opening and slidable therein to project outwardly beyond the outer end of said inner sleeve member, said outer sleeve member being provided adjacent its inner end with an internal collar and having at its outer end an inturned flange surrounding said mandrel and formed with an annular jaw face overlying and opposed to the said outer end of the inner sleeve member, said inner sleeve member being provided at its outer end with an annular jaw face surrounding said mandrel and facing the jaw face of said outer sleeve member, and a compression coil spring disposed within the outer sleeve member and fitting over the inner sleeve member and compressed between the said collars on said sleeve members to resiliently urge the opposed jaw faces thereof together.

11. Filament coiling apparatus comprising, in combination, a coiling spindle having an axially extending mandrel guide opening at one end

thereof, a coiling mandrel extending axially of said spindle through said guide opening and slidable therein to project outwardly beyond the said spindle end, said spindle being provided at said end with a pair of opposed rotatively-interlocked annular jaw members surrounding said mandrel and relatively movable axially of the spindle, resilient means normally urging said jaw members together to clamp an end of the filament wire therebetween and hold it across the portion of the mandrel projecting outwardly beyond the said spindle end, jaw actuating means engageable with one of said jaw members for moving it axially of the spindle and away from the other of said jaw members, and feed means operatively associated with said jaw actuating means and said jaw members for inserting an end of the filament wire between the jaw members when separated by said actuating means.
